Primary Examiner — Karen E Kearney*Assistant Examiner* — Carissa C Fitts(74) *Attorney, Agent, or Firm* — Baumgartner Patent Law; Marc Baumgartner(57) **CLAIM**

The ornamental design for a light, as shown and described.

DESCRIPTION

FIG. 1 is a perspective view of a first embodiment of a light embodying my new design;

FIG. 2 is a front view of the light of FIG. 1;

FIG. 3 is a back view of the light of FIG. 1;

FIG. 4 is a first side view of the light of FIG. 1;

FIG. 5 is a second side view of the light of FIG. 1;

FIG. 6 is a top view of the light of FIG. 1;

FIG. 7 is a bottom view of the light of FIG. 1;

FIG. 8 is a perspective view of a second embodiment of a light embodying my new design;

FIG. 9 is a front view of the light of FIG. 8;

FIG. 10 is a back view of the light of FIG. 8;

FIG. 11 is a first side view of the light of FIG. 8;

FIG. 12 is a second side view of the light of FIG. 8;

FIG. 13 is a top view of the light of FIG. 8; and,

FIG. 14 is a bottom view of the light of FIG. 8.

The broken lines show portions of the article not claimed and form no part of the claimed design.

1 Claim, 6 Drawing Sheets(56)
